(57) **CLAIM**

The ornamental design for a safety medical needle assembly, as shown and described.

DESCRIPTION

FIG. 1 is a right side elevational view of a safety medical needle assembly according to our invention, showing in broken lines how the safety medical needle assembly is attached to a medical syringe;

FIG. 2 is a left side elevational view thereof;

FIG. 3 is a top plan view thereof;

FIG. 4 is a bottom plan view thereof;

FIG. 5 is a front elevational view thereof;

FIG. 6 is a rear elevational view thereof;

FIG. 7 is a right side elevational view thereof, showing the safety medical needle assembly after use;

FIG. 8 is a right side elevational view of a second embodiment of the safety medical needle assembly according to our invention;

FIG. 9 is a left side elevational view thereof;

FIG. 10 is a top plan view thereof;

FIG. 11 is a bottom plan view thereof;

FIG. 12 is a front elevational view thereof;

FIG. 13 is a rear elevational view thereof; and,

FIG. 14 is a right side elevational view thereof after use.

The broken line showing of FIGS. 1 and 8 is for illustrative purposes only and forms no part of the claimed design.
